CLAIM

The ornamental design for a bottle, as shown and described.

DESCRIPTION

FIG. 1 is a top, front, and right side perspective view of a first embodiment of a bottle depicting the new design;

FIG. 2 is a right side elevation view thereof;

FIG. 3 is a front elevation view thereof;

FIG. 4 is top plan view thereof;

FIG. 5 is a bottom plan view thereof;

FIG. 6 is a top, front, and right side perspective view of a second embodiment of a bottle depicting the new design;

FIG. 7 is a right side elevation view thereof;

FIG. 8 is a front elevation view thereof;

FIG. 9 is top plan view thereof; and,

FIG. 10 is a bottom plan view thereof.

The dashed line shown in the drawings is for illustrative purposes only and forms no part of the claimed design. The dot-dash-dot line shown in the drawings defines the boundary of the claim and forms no part of the claimed design.
